UNITED STATES PATENT OFFICE.

JOHN B. MCPHERSON, OF BUNKER HILL, ILLINOIS.

BRIDGE.

SPECIFICATION forming part of Letters Patent No. 252,487, dated January 17, 1882.

Application filed June 28, 1881. (No model.)

To all whom it may concern:

Be it known that I, JOHN B. MCPHERSON, of Bunker Hill, in the county of Macoupin and State of Illinois, have invented certain new and useful Improvements in Bridges; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation of my improved bridge. Fig. 2 is a bottom plan of the same. Fig. 3 is a longitudinal vertical section through one of the chords and braces, and Fig. 4 is a cross-section through one of the bolsters with its clamping-rods and clamp.

Similar letters of reference indicate corresponding parts in all the figures.

My invention relates to bridges made of wood or chiefly of wood, calculated to have a span of from forty to seventy feet, more or less; and it consists in the improvements hereinafter set forth, and particularly pointed out in the claims.

In the annexed drawings, A A are the bed-timbers, which rest upon the pier-posts.

B B are bolsters, made preferably of cast-iron, of the shape shown in the drawings, from which it will be seen that each bolster consists of a bottom plate or body, a, made with two laterally-projecting ears, b b, which are bored through vertically and countersunk on their under side for the insertion of the headed clamping-rods C. At its outer end plate a is cast with a rounded shoulder, c. The plate or base a is bored through longitudinally, as shown at d, Fig. 3, for the insertion and attachment of the ends of the wire rope or chord D, the heads e of which are embedded in countersunk recesses d'.

E is the sleeper or string-piece, of which there may be one or more passing from end to end, resting upon and bolted to the bed-timbers A A.

F is the central cross-joist, and G G the joist-braces, each pair of which (one on each side of the joist) is arranged in the shape of a cross, with the ends mortised into the bed-timbers A and central joist, F, respectively, so as

to form a firm and rigid bottom for the support of the planks.

H H are the struts or braces, the ends of which are stepped in the shouldered bolsters B, as shown at h, and held in place by a cross-piece or clamp, I, which is beveled to fit the angle of the strut. The upper ends of the tie-bolts or clamping-rods C C are inserted through and nutted to the projecting ends of the clamp-plate I, the nuts being tightened down so as to bind the beveled under side of the plate firmly against the strut.

K is the tension-rod, the upper end of which is inserted through and nutted to a cap-plate, k, placed over the joint of the struts H H, while its lower end is inserted through and nutted to the under side of the projecting ends of the cross-joist F, on the outside of the chord D.

This bridge, while being simple and inexpensive in its construction, is capable of standing a heavy strain, and can be made in single spans of from forty to seventy feet, and even more, without additional braces or other strengthening devices.

I am aware that it is old to employ, in connection with the bolsters, the bed-pieces, and the inclined timbers, obliquely-arranged yoke or staple shaped bolts; to employ bolsters with the inclined pieces or arches seated therein and having the stringers or rods passing through them; to employ underneath shouldered bolsters in connection with side pieces, rods, and bolts, securing them together; to employ right-angled bolsters with the inclined pieces or timbers and rods bolted to the bolsters, and bolts extending from the ends of said bolsters upon the sides of the inclined pieces, and to employ bolsters adapted to permit the chords or rods to pass through and be bolted to them and form shoulders for the lower ends of the inclined pieces to rest against, with bolts passing through them and the inclined pieces.

Having thus described my invention, I claim and desire to secure by Letters Patent of the United States—

1. The combination, in a bridge of the described class, of the end or bed timbers, A A, shouldered bolsters B, having perforated ears b b and longitudinal countersunk bore d d', headed chords D, made of wire rope, struts or

braces H, beveled clamping-plates I, and nutted tie-bolts C C, all constructed and combined substantially as and for the purpose herein shown and set forth.

- 5 2. The bolster B, composed of a longitudinally-perforated base-plate, a, having shoulder c and laterally-projecting perforated ears b b, as and for the purpose herein shown and specified.

In testimony that I claim the foregoing as to my own I have hereunto affixed my signature in presence of two witnesses.

JOHN B. McPHERSON.
